AUTOMATIC STOP MECHANISM FOR LOOMS

Irvin K. Hauseman, Pottstown, Pa.

Application November 29, 1937, Serial No. 177,149

19 Claims. (Cl. 139—355)

This invention relates to automatic stop mechanisms for looms and more particularly to a stop mechanism operated by means associated with the heddle frames to stop the loom whenever a 5 warp thread breaks or becomes abnormally slack.

More specifically, the invention relates to a means associated with a heddle frame and operable in response to a broken or excessively slack warp thread to close an electric circuit and thereby operate a magnetic clutch or other control device which will immediately and automatically stop the loom. Such stopping of a loom prevents waste, saves time, and assures the 10 production of a woven product free from defects.

Automatic mechanisms for stopping looms have been used heretofore with varying degrees of success. However, insofar as is known, none of these has ever been designed to facilitate the 15 quick location of a broken or slack warp thread. One of the features and advantages of the present invention is that it provides relatively simple means for enabling a loom operator or weaver to immediately locate a broken or slack warp 20 thread. This feature results in the saving of the time normally wasted by the weaver in searching for the heddle whose thread is responsible for stopping of the loom. According to the present invention, such heddle will visibly project above the remaining heddles and hence can be instantly 25 located by the weaver.

The principal object of the invention is to provide an improved means for use in a loom for stopping said loom whenever a warp thread 30 breaks or becomes excessively slack.

Another object of the invention is to provide improved means associated with a heddle frame for completing an electric circuit which will stop the loom when any thread controlled by the particular heddle frame is broken or becomes unduly 35 slack.

Still another object of the invention is to provide means which will enable a weaver to instantly locate a heddle which has a broken or slack thread and thereby save the time usually expended in an effort to locate such heddle.

A further object of the invention is to provide an improved heddle which will function to complete a circuit for stopping a loom when the warp 45 thread controlled thereby is too slack or is broken.

A still further object of the invention is to provide an improved heddle which will automatically 50 serve as a signal to indicate that the

warp thread controlled thereby is broken or is excessively slack.

A still further object of the invention is to provide a readily shiftable clamp means adapted to avoid the sagging of the heddle supporting 5 bars normally caused by the weight of the heddles and the tension of the warp threads.

Other objects and advantages of the invention will be apparent from the following description taken in conjunction with the accompanying 10 drawings in which:

Figure 1 diagrammatically illustrates the invention applied to one heddle frame of a loom;

Figure 2 is an enlarged sectional view taken on the line 2—2 of Figure 1 showing the improved shiftable clamp means for supporting and taking the sag out of the heddle supporting bars. In this view, however, the latch of the clamp is shown in open position;

Figure 3 is an elevational view of the shiftable 20 clamp shown in Figure 2;

Figures 4, 5 and 6, respectively, are diagrammatic views illustrating various positions which a heddle may assume relatively to its supporting bars; and

Figure 7 is a perspective view of an element 25 for retaining the contact supporting bracket arms shown in Figure 1 in adjusted position.

Referring particularly to Figure 1 of the drawings, a heddle frame is generally designated by 30 the numeral 1. This frame comprises a top rail 2 and a bottom rail 3. These rails are preferably made of wood for the sake of lightness. The rails 2 and 3 are connected at their ends by vertically extending metallic struts 4 and 5 which 35 maintain the rails in rigid spaced relation. The rails 2 and 3 are provided with hooks 6 and 7, respectively, which afford means for connecting the heddle frame 1 to the harness operating mechanism of the loom (not shown).

A heddle supporting bar 8 is located adjacent the top rail 2 and the opposite ends thereof project through openings 9 in the side struts 4 and 5. The lower edge of the heddle supporting bar 8 is provided with a bead 10, the important purpose 45 of which will be set out more fully hereinafter. A second heddle supporting bar 11 is located adjacent the lower end of the heddle frame 1 near the bottom rail 3, and the opposite ends thereof project through openings 12 in the side struts 50 4 and 5.

A rigid rod 13 is secured by screw eyes 14 to one longitudinal edge of the upper rail 2, and a similar rod 15 is secured by screw eyes 16 to one longitudinal edge of the bottom rail 3. The 55

heddle supporting bars 8 and 11 are connected to the rods 13 and 15, respectively, by supporting means or clamps 17 and 18, respectively.

A series of heddles 19 extend from the heddle supporting bar 8 to the heddle supporting bar 11. The supporting clamps 17 and 18 retain the heddle supporting bars 8 and 11, respectively, in predetermined spaced relation to the rods 13 and 15 and prevent said heddle supporting bars from sagging due to the weight of the heddles 19 and the tension of the warp threads acting upon said heddles.

As shown in detail in Figures 2 and 3, the clamping means 17 comprises a bar 20 which has an aperture 21 at one end thereof for receiving one of the rods 13 or 15. The lower end of the bar 20 is cut away as indicated at 22 to provide a notch or recess 23 for receiving one of the heddle supporting bars 8 or 11. In the present instance, the upper heddle supporting bar 8 is shown seated in the recess 23 with the bead 10 thereof engaging a bottom portion 24 of said recess and the upper edge 10^a thereof in engagement with a shoulder 25 formed at the upper portion of said recess. The heddle supporting bar 8 is retained in the recess 23 by a latch 26 which is pivotally mounted upon the bar 20 by a pin 27. The latch 26 is provided with a recess 28 which has shoulders 29 and 30 adapted to engage the upper and lower edges 10^a and 10, respectively, of the heddle supporting bar 8. The lower end of the latch 26 is provided with a transverse projection 31 which cooperates with a recess 32 formed in the lower end of the bar 20 to retain the latch 26 in locked position. The latch 26 is preferably made of some resilient material which will permit the end thereof carrying the projection 31 to be sprung away from the bar 20 to facilitate locking and release of said latch.

It will be clear from the foregoing, that when the latch 26 is in locked position, the heddle supporting bar 8 will positively be prevented from moving vertically relatively to the supporting clamp 17 by reason of the engagement of the shoulders 25 and 29 with the upper edge 10^a thereof and engagement of the shoulders 24 and 30 with the lower edge 10 thereof. It will be further apparent, that when it is desired to shift the clamp 27 from one position to another along the heddle supporting bar 8, it is only necessary to release the latch 26 and to spring the heddle supporting bar 8 upwardly to such an extent as to clear the projection 33 of the cut-away portion 22. The clamp 17 may then be shifted longitudinally along the rod 13 to any desired position and attached to said heddle supporting bar between any pair of heddles 19 and secured in such position by returning the latch 26 to its locking position.

It is desirable that the heddle supporting bars 8 and 11 not only be retained against longitudinal sagging but also be prevented from flexing laterally. In order to accomplish the latter, a spring 34 is mounted so that one end thereof 35 is relatively fixed with respect to the side struts 4 and 5 and the opposite end 36 thereof extends into a recess 37 formed in the opposite ends of the heddle supporting bar 8. The tension of the springs 34 is such that it places the heddle supporting bar 8 under longitudinal tension and thus maintains said bar in a taut and rigid condition. The lower heddle supporting bar 11 is maintained taut by springs 38 similar to the springs 34.

One of the heddles is shown in enlarged detail in Figures 4, 5 and 6. Each of the heddles is provided at its upper end with an elongated opening 40 having an upper series of arcuate projections 41 extending toward each other from the opposite side walls thereof and a second series of similar arcuate projections 42 disposed adjacent to and below the projections 41. The arcuate projections 41 and 42 are adapted to cooperate with the beaded portion 10 of the upper heddle supporting bar 8 in a manner to retain a heddle in raised position above the remaining heddles in the event that the thread controlled by the particular heddle breaks or becomes excessively slack, all in a manner which will be fully set out hereinafter.

Each of the heddles 19 is provided adjacent its lower end with another elongated opening 45. This opening has plain sides in contrast to the sides of the upper opening 40. The lower opening 45 is adapted to receive the lower heddle supporting bar 11.

Intermediate the openings 40 and 45, each of the heddles is provided with an eye 46 through which a warp thread (not shown) is threaded. Each of the heddles 19 is also provided intermediate the openings 40 and 45, and above the eye 46, with an elongated slot 47 of such dimensions as to slidably and snugly receive therein a contact bar 48. This contact bar is arranged so that it passes through the slot 47 of each of the heddles 19.

Reverting to Figure 1, the contact bar 48 is so arranged with respect to the heddle frame 1 that the opposite ends 49 and 50 thereof extend through recesses 51 and 52 formed in the side struts 4 and 5, respectively, and permit said contact bar to slide vertically relatively to said side struts. The ends 49 and 50 of the contact bar 48 are connected with brackets 53 and 54 secured to the side struts, by tension springs 55 and 56, respectively, which continuously tend to urge said contact bar into engagement with the upper end walls of the recesses 51 and 52. The purpose of the springs 55 and 56 is to facilitate the return of the heddles 19 to their raised or uppermost position when the heddle frame 1 is lowered by the loom harness. This is done through engagement of the top face contact bar 48 with the upper end walls 57 of the slots 47. It will be clear that the tension of the warp threads will also tend to return said heddles to their relatively raised position and that the pull exerted by the springs 55 and 56 supplements that of the tension of the warp threads.

The contact bar 48 is provided with a channel 58 extending into one longitudinal edge thereof. A strip of insulating material 59 of U-shape in cross-section is seated in said channel. A contact strip 60 is seated in the channel of said U-shaped insulated strip. The contact strip 60 and the insulating member 59 extend for substantially the full length of the contact bar 48, as is clearly shown in Figure 1. It will be noted, however, that one end 62 of the contact strip 60 terminates short of the side strut 4 and that the opposite end of said contact bar is notched as indicated at 63 to avoid possible contact with the side strut 5, and further, that said contact member terminates in a projection 64 located adjacent the notch 63.

The projection 64 of the contact bar 60 is arranged to engage a contact 65 carried by a bracket 66 secured to the side strut 5. A spring 67 is interposed between the contact 65 and the

bracket 66 and permits said contact to yield slightly when engaged by the projection 64. The bracket 66 is insulated from the side strut 5 by an insulating member 68 and is secured to said strut by screws 69 which are insulated from the bracket 66 by short tubular non-metallic sleeves 70. The bracket 66 is provided with a vertically extending portion 71 which carries a wear strip 72 insulated from said vertical portion by a piece 10 of insulating material 73. The parts 72 and 73 are secured to the portion 71 by screws 74 which are insulated from said portion by non-metallic sleeves 75. The purpose of the wear strip 72 is to prevent the end 50 of the contact bar 48 from engaging the portion 71 of the bracket 66 and inadvertently completing the circuit to stop the loom. A further purpose of the strip 72 is to assure that the projecting portion 64 of the contact strip 60 will be guided so as to properly 20 engage the contact 65.

The bracket 66 is further provided with a horizontal projection 75 extending laterally from the vertical portion 71. The horizontal projection 75 carries a contact member 76 resiliently supported by a spring 77. The contact 76 is adapted to engage a metallic contact 78 which is carried by a plunger member 79 insulated from the contact 78 by a strip of insulating material 80. The plunger 79 is slidably mounted in one end of a bracket 81 and is resiliently supported by a spring 82. The bracket 81 is supported by a second bracket member 82 secured to one side frame 83 of the loom. The brackets 81 and 82 are provided with elongated slots 84 and 85, respectively, 35 which permit longitudinal and transverse adjustment of the bracket 81 with respect to the bracket 82. The brackets 81 and 82 are clamped together by a bolt 86 which projects through the elongated openings 84 and 85. This bolt is provided with a square shank 87, see Figure 7, which prevents turning of the bracket members 81 and 82 relatively to each other.

A pair of brackets 88 and 89 corresponding to the brackets 81 and 82, respectively, is mounted upon the other side frame 90 of the loom. The brackets 88 and 89 are relatively adjustable with respect to each other and may be locked in any desired position of adjustment by a bolt 91 having a square shank 92 similar to that of the bolt 86. The bracket member 88 carries a contact 92 which is movable relatively thereto but is maintained spaced therefrom by a compression spring 93. The contact 92 engages a cooperating contact 94 which is carried by a bracket 95 similar 50 to the bracket 66. However, in contrast with the bracket 66, the bracket 95 is not insulated from the side strut 4 but is directly connected thereto by screws 96. The contact 94 is associated with a spring 97 which yieldably supports the same relatively to the bracket 95. Still another contact 98 is carried by the bracket 95 and is arranged to be engaged by the end 49 of the contact bar 48. The contact 98 is yieldably supported on the bracket 95 by means of a compression spring 99.

A wire 101 is connected to the insulated contact 78, and a second wire 102 is connected to the contact 92. The wires 101 and 102 form part of an electrical circuit which may include as a 70 part thereof, some means, such as a magnetic clutch, for stopping the operation of the loom whenever the circuit is established or completed. In accordance with the present invention, such circuit is completed whenever a warp thread breaks or is excessively slack. The manner in 75

which the circuit is completed under the conditions specified, will now be explained.

It will be assumed that each of the heddles 19 has a warp thread extending through its eye 46 and that the warp thread extending through one of said heddles, for example, heddle 19^a of Figure 1, is either broken or abnormally slack. When the heddle frame 1 is raised such warp thread will permit the heddle 19^a to move upwardly along with said heddle frame. This upward movement occurs by virtue of the engagement of the lower arcuate projections 42 of the heddle 19^a with the beaded portion 10 of the heddle supporting bar 8. Since the thread associated with heddle 19^a does not in any way restrain said upward movement, said heddle will, of course, be free to rise with and be supported by the bead 10 of the heddle supporting bar 8 upon raising of the heddle frame. At the same time, the normal tension of the warp threads associated with the remaining heddles 19 will tend to restrain upward movement of said heddles during the raising of said heddle frame. The result of this is that the beaded portion 10 of the heddle supporting bar 8 will move upwardly relatively 25 to the heddles 19, sliding past the projections 41 and 42 until the end walls 57 of the slots 47 of the heddles engage with the upper face of said contact bar 48. Upon such engagement, the contact bar will be restrained against upward movement until the projection 64 of the contact strip 60 is brought into engagement with the contact 65 and the end 49 of the contact bar 48 is brought into engagement with the contact 98. 30

It will be apparent from the foregoing that the tension of the warp threads of the heddles 19 is sufficient to overcome the resistance offered by the arcuate projections 42 and 41 to the upward passage therebetween of the heddle supporting bar 8 and its beaded portion 10. The passage of said beaded portion between the projections 42 and 41 is permitted by the flexible construction of the upper end of the heddles which provides for flexing of the longitudinal walls defining the apertures 40 to thereby permit a slight spreading apart of said walls when the beaded portion 10 engages the projections 42 and 41. It will be further apparent that the tension of the warp threads of the heddles 19 is also such as to overcome the tension of the springs 55 and 56 so that the contact bar 48 and the contact strip 60 will be restrained to engage the yieldable contacts 65 and 98 carried by the heddle frame 1, as afore-described. 35

With the warp heddle 19^a supported by the bead 10 and being raised as the heddle frame 1 is elevated, and the remaining warp heddles 19 restraining the contact bar 48 from moving upwardly with said heddle frame, it will be obvious 40 that the contact strip 60 will be brought into engagement with the lower end wall 103 of the elongated slot 47 of the heddle 19^a to thus establish an electrical connection between said contact strip and the contact bar 48, as illustrated in Figure 5. Due to the resilient nature of the heddle material, the projections 42 offer such impedance or resistance to the downward movement of the heddle 19^a over the bead 10 that the contact strip 60 engages the lower end wall 103 45 with sufficient pressure to insure establishment of the desired circuit. In the event that the contact bar 48 pulls the projections 42 past the bead 10, the heddle 19^a will not drop by gravity but will be held raised by the frictional engagement of 50

the projections 41 with the bar 6, as clearly shown in Figure 6.

As will be apparent to those familiar with the weaving art, the heddle frame 1 is raised and lowered at proper intervals by a suitable harness (not shown). According to the present invention, the heddle frame is elevated to such position that the contacts 76 and 94 carried thereby engage the contacts 78 and 92, respectively, carried by the loom frame, as clearly shown in Figure 1. The electrical connection between the contact bar 48 and the strip 60 through the heddle 19^a, and the engagement of said bar and strip with the contacts 65 and 98, respectively, is preferably established just before the contacts 76 and 94 of the heddle frame engage the contacts 78 and 92, respectively. With the engagement of the parts as described above, it will be apparent that an electrical circuit will be completed between the wires 101 and 102, and that as a result thereof any suitable means associated with the loom and circuit will be actuated to stop the loom.

It will be clear that the heddle 19^a will project above the remaining heddles 19, as shown in Figure 1, when the loom is stopped, thus enabling the operator to instantly locate the heddle which is responsible for the stopping of the loom.

Upon restarting of the loom, or upon any lowering of the heddle frame 1 by the harness, the tension on the springs 55 and 56 will be released and these springs will slide the contact bar 48 upwardly relatively to said frame and as a result of the engagement of the upper face of the contact bar 48 with the upper end wall 57 of the elongated recesses 41, the warp heddles 19 will be urged upwardly. Such engagement of the contact bar is illustrated in Figure 4. In order for the heddles 19 to be moved upwardly with respect to the supporting bar 8, it will be obvious that the side walls defining the elongated apertures 40 must be again sprung apart sufficiently to permit the projections 41 and 42 to pass the beaded portion 10 of said supporting bar. The upward movement of the bar 48 relatively to the heddle frame is limited by the end walls of the recesses 51 and 52 of the side struts 4 and 5, respectively.

While the stop mechanism has been described with reference to one heddle frame, it is to be understood that each heddle frame of a given loom is to be similarly equipped so that the loom can be stopped by the excess slack or breakage of any warp thread. It is to be further understood that in lieu of providing individual contacts on the loom frame for each heddle frame, suitable contact bars adapted to be engaged by a plurality of heddle frames may be used. Likewise it is to be still further understood that the invention is not limited to the particular arrangement of contacts shown, and further, that the invention may be practiced with a contact bar and with heddles provided with means for impeding the vertical movement thereof relatively to a supporting bar different from the specific forms disclosed herein. Thus, numerous modifications and changes may be made in the invention without departing from the spirit thereof or from the scope of the annexed claims.

Having described my invention, I claim:

70. 1. In combination, a warp heddle having an opening, a heddle supporting bar extending through said opening, and cooperating surfaces on said warp heddle and said heddle supporting bar arranged and constructed to maintain said warp heddle in raised position relative to said

heddle supporting bar when a warp thread associated with said warp heddle becomes broken or unduly slack.

2. In combination, a warp heddle having an opening, and a heddle supporting bar arranged in said opening, said warp heddle normally being vertically movable with respect to said heddle supporting bar, said heddle having means cooperable with said heddle supporting bar for preventing downward movement thereof by gravity relative to said supporting bar when a thread controlled thereby is broken or unduly slack.

3. In combination, a warp heddle having an opening, and a heddle supporting bar extending into said opening, said warp heddle normally being vertically movable with respect to said heddle supporting bar, said heddle supporting bar having means for preventing downward movement thereof by gravity relative to said supporting bar when a thread controlled thereby is broken or unduly slack.

4. In combination, a warp heddle having an opening, and a heddle supporting bar operably disposed in said opening, said heddle normally being vertically movable with respect to said heddle supporting bar, said warp heddle and said heddle supporting bar having means mutually cooperable to maintain said warp heddle in raised position relative to said heddle supporting bar when a warp thread associated with said heddle becomes broken or unduly slack.

5. Means for use in looms comprising a warp heddle having an opening, and a heddle supporting bar extending through said opening, said heddle supporting bar having a beaded portion and said warp heddle having means cooperating with said beaded portion for maintaining said warp heddle in raised position relative to said heddle supporting bar when a warp thread associated with said heddle becomes broken or unduly slack.

6. Means for use in looms comprising a warp heddle having an opening, and a heddle supporting bar disposed in said opening, said heddle supporting bar having a beaded portion, and said warp heddle having a projection cooperating with said beaded portion for maintaining said warp heddle in raised position relative to said heddle supporting bar when a warp thread associated with said heddle becomes broken or unduly slack.

7. A heddle for use with a heddle supporting bar in a loom to control a warp thread, comprising: a thin strip of resilient material having an opening defined by opposed end and side walls, at least one of said side walls being provided with a projection extending toward the opposite side wall and cooperable with such heddle supporting bar, whereby to maintain said heddle in raised position relatively to such heddle supporting bar when a thread controlled by said heddle breaks or becomes unduly slack.

8. In a loom harness, a frame, a pair of bars extending across said frame, a plurality of warp heddles mounted on said bars and normally vertically movable relatively to said frame, each of said warp heddles having elongated openings receiving said bars, and means for frictionally preventing vertical downward movement of said warp heddles by gravity, respectively, relatively to at least one of said bars when a thread controlled by a given heddle becomes broken or unduly slack.

9. In a loom harness, a frame comprising top and bottom rails and metallic side struts connecting said rails, a pair of bars disposed between

5 said side struts, a plurality of warp heddles supported by said bars and movable vertically with respect thereto, each of said warp heddles having an elongated slot, a contact bar slideable vertically relatively to said side struts and said warp heddles and extending through said elongated slots, the sides defining said elongated slots being in snug engagement with said contact bar, and means carried by said frame and connected 10 with said contact bar tending to urge said contact bar into engagement with the upper end walls of said elongated slots, whereby to facilitate the return of the warp heddles to their raised or uppermost position when said heddle frame is lowered by a loom harness:

10. Means for establishing an electric circuit for stopping a loom comprising: a frame having top and bottom rails and side struts connecting said rails, a pair of bars disposed between said 15 side struts, a plurality of warp heddles supported by said side struts and normally movable vertically with respect thereto, each of said warp heddles having an elongated slot, a contact bar slideable vertically relatively to said side struts and 20 said warp heddles and extending through said elongated slots, the sides defining said slots being in snug engagement with said contact bar, said contact bar comprising a channeled member, a contact strip, and means insulating said 25 channeled member from said contact strip, and means constructed and arranged to support the given heddle in raised position relatively to said bars when a warp thread controlled by said heddle breaks or is unduly slack, whereby when said 30 frame is raised by a loom harness, said contact strip will engage a lower end wall of the elongated slot in said heddle and an electric circuit will be completed between said channeled member and said contact strip.

11. Means for establishing an electrical circuit for stopping a loom, comprising: a heddle frame, a pair of bars mounted in said frame, a plurality of warp heddles supported by said bars and movable vertically with respect thereto, each of said 45 warp heddles having an elongated opening, a contact bar slideable vertically relatively to said frame and said warp heddles, said contact bar extending through said elongated openings, said contact bar comprising a channeled member, a contact strip, and means insulating said channeled member from said contact strip, the sides defining said elongated opening being in snug engagement with said channeled member, and contacts carried by said frame arranged to be engaged by said contact bar upon upward movement of said heddle frame, said contact strip being arranged to engage a lower end wall of the elongated opening of any warp heddle whose thread is broken or is abnormally slack to thereby complete 50 an electrical connection between said contact strip and said channeled member.

12. In combination, a heddle frame comprising top and bottom rails and side struts connecting said rails, said side struts being provided with aligned elongated openings; a plurality of warp heddles between said side struts, each of said heddles having an elongated opening; a contact bar extending through the openings of said side struts and warp heddles, said contact bar comprising a channeled member and a contact strip, and means insulating said channeled member from said contact strip; resilient means tending to raise said contact bar relatively to said struts; and contact members carried by said side struts, said contact members being arranged so

that one contact member is engaged by said channeled member and the other of said contacts is engaged by said contact strip when said heddle frame is raised by a loom harness and the raising of said contact bar is restrained by the tension of the threads associated with said warp heddles.

13. A heddle frame comprising top and bottom rails and side struts connecting said rails, said side struts being provided with aligned elongated 10 openings, a contact bar extending through said openings, said contact bar comprising a channeled member, a contact strip, and means insulating said channeled member from said contact strip, bars extending between said side struts, a plurality of warp heddles supported by said bars and each provided with an opening to receive said contact bar, and contact members carried by said struts, one of said contact members being arranged to be engaged by said channeled member 15 and the other of said contact members being arranged to be engaged by said contact strip, said contact bar being arranged to be lowered relatively to said side struts by said heddles, upon upward movement of said frame, to engage said 20 contacts.

14. Means for establishing an electrical circuit for stopping a loom, comprising: a frame, a plurality of warp heddles, each of said warp heddles having an elongated slot, means supporting said 25 heddles in said frame so that they can move vertically relatively thereto, contact members carried by said frame, a contact bar disposed transversely of said frame and extending through said elongated slots and having end portions arranged to engage said contact members, said contact bar being arranged to engage with said contact members when said heddle frame is raised, said contact bar being engageable by the upper end walls of said elongated slots and movable vertically with respect to said frame by said 30 heddles, the lower end walls of said slots normally being free from engagement with said contact bar but being engageable therewith to establish an electric circuit when a warp thread 35 controlled by any one of said heddles breaks or becomes unduly slack.

15. A mechanism for completing an electric circuit to thereby stop a loom, comprising: a pair of loom side frames, a heddle frame vertically 40 movable with respect to said loom side frames, contact members carried by said heddle frame and said loom frames arranged to mutually engage to establish an electric circuit as the heddle frame nears its upper limit of movement, a plurality of warp heddles carried by said heddle frame, and means constructed and arranged so 45 that when a warp thread controlled by one of said warp heddles breaks or becomes unduly slack an electrical circuit will be established to stop said 50 loom.

16. In a loom harness, a frame, a plurality of warp heddles each having an elongated slot and an opening for a warp thread normally under tension, means supporting said warp heddles in 55 said frame so that they can move vertically relatively thereto, and a contact bar slideably mounted in said frame and extending through said elongated slots, said contact bar being engageable by the upper end wall of each said slot and 60 movable vertically with respect to said frame by said warp heddles when said frame raises the warp heddles against the tension of the warp threads, said heddle supporting means including instrumentalities for restraining free downward 65

movement of a warp heddle whose thread is broken or unduly slack, the lower end wall of each of said slots of said warp heddles normally being free from engagement with said contact bar but being engageable therewith when downward movement thereof is restrained by said instrumentalities.

17. Means for establishing an electric circuit for stopping a loom, comprising: a frame, contact members carried by said frame, heddle supporting bars extending across said frame, a plurality of warp heddles supported by said bars and movable vertically with respect to said frame, each of said warp heddles having an elongated slot and an opening for a warp thread normally under tension, and a contact bar operatively associated with said contact members, said contact bar being slidably mounted in said frame and extending through said elongated slots, said contact bar being engageable by the upper end wall of said slots and movable vertically with respect to said frame by said warp heddles into engagement with said contact members when said frame raises the warp heddles against the tension of the warp threads, said warp heddles including means cooperating with said supporting bars for restraining free vertical movement of a warp heddle whose thread is broken or unduly slack, the lower end walls of said slots normally being free from engagement with said contact bar but being engageable therewith when a warp thread controlled by any one of said heddles breaks or becomes unduly slack.

18. Means for establishing an electric circuit for stopping a loom, comprising: a frame, contact members carried by said frame, a pair of heddle supporting bars extending across said frame, a plurality of warp heddles supported by said bars and movable vertically relatively to said frame and bars, each of said warp heddles hav-

ing an elongated slot and an opening for a warp thread normally under tension, a contact bar operatively associated with said contact members and including an upper metallic channel member and a lower contact strip insulated from said channel member, said channel member and contact strip each being arranged to engage a separate contact member, said contact bar being slidably mounted in said frame and extending through the elongated slots of said warp heddles, said contact bar being engageable by the upper end walls of said elongated slots and movable vertically with respect to said frame by said heddles into engagement with said contact members when said frame raises the warp heddles against the tension of the warp threads, said warp heddles including means cooperating with said supporting bars for restraining free vertical movement of a warp heddle whose thread is broken or unduly slack, the lower end walls of said slots normally being free of engagement with said contact bar but being engageable therewith to complete an electric circuit between said channel member and contact strip when a warp thread controlled by any one of said heddles breaks or becomes unduly slack.

19. In combination, a warp heddle comprising a thin strip of resilient material having an opening defined by opposed end and side walls, at least one of said side walls being provided with a projection extending toward the opposite side wall; and a heddle supporting bar extending through said opening in said warp heddle, said heddle normally being vertically movable relative to said supporting bar, said projection of said heddle being arranged to maintain said heddle in raised position relative to said heddle supporting bar when a thread controlled by said warp heddle breaks or becomes unduly slack.
